UNITED STATES PATENT OFFICE.

LYMAN L. DENNICK, OF CHICAGO, ILLINOIS.

DESIGN FOR A PICTURE-FRAME.

Specification forming part of Design No. 5,103, dated July 11, 1871.

To all whom it may concern:

Be it known that I, LYMAN L. DENNICK, of the city of Chicago, in the county of Cook and State of Illinois, have invented and produced a new and original Design for Picture-Frames, of which the following is a description:

The central rectangular piece or frame A, which receives the picture, glass, &c., is formed from a piece of wood. To the face of the central piece A I design to attach ornaments *a a* of different-colored woods. The picture, or its mat portion shown, terminates with the white outline. A fret-work, C, of open ornamental design, is attached to the sides or edges of the central frame A, and is usually formed of thin and different-colored wood. The ornaments *a a* C are secured to the central frame either by the use of glue, dowels, or any other convenient method.

What I claim as my design, and desire to secure by Letters Patent, is—

1. The central rectangular frame A having fret-work C around its sides, substantially as shown.
2. The ornamental design for picture-frames, consisting of the central rectangular frame A provided with ornaments *a a*, and open ornamental fret-work C around its sides, as shown and described.

In witness whereof I have hereunto signed my name in the presence of two subscribing witnesses.

LYMAN L. DENNICK.
